UNITED STATES PATENT OFFICE.

SAMUEL S. WILLIAMSON, OF PHILADELPHIA, PENNSYLVANIA.

FLUSH-TANK.

1,232,147.

Specification of Letters Patent.

Patented July 3, 1917.

Application filed November 3, 1916. Serial No. 129,339.

To all whom it may concern:

Be it known that I, SAMUEL S. WILLIAMSON, a citizen of the United States, residing at Philadelphia, in the county of Philadelphia and State of Pennsylvania, have invented new and useful Improvements in Flush-Tanks, of which the following is a specification.

My invention relates to new and useful improvements in flush tanks for water closets and the like, and has for its object to provide means whereby the proper level of water may be maintained in the tank until it is desired to withdraw the same, which by giving the stationary siphon an initial start the tank will be emptied to a point level with the intake of the siphon, and thereafter no further water can be withdrawn from the tank until the tank has been refilled to its original water level, thus avoiding the waste of water which has heretofore been caused by leakage, emptying the tank before it has sufficient water therein to properly flush the closet and from the leaking of the flush valve.

A further object of the invention is to provide a quick acting mechanism for giving the stationary siphon its initial start.

With these ends in view, my invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this specification, in which—

Figure 1, is a section of a tank, a portion thereof being left in elevation to more clearly illustrate my invention.

Fig. 2, is a cross section at the line $\alpha-\alpha$ of Fig. 1, the intake float ball being omitted.

Fig. 3, is a plan view, a portion of the front wall of the tank being sectioned away to clearly illustrate the location and construction of the quick acting mechanism.

Fig. 4, is an enlarged detailed plan view of the lift for giving the initial start to the siphon.

Fig. 5, is a section of Fig. 4, the hinged leaves being shown in full lines in their ele-

vated position and in dotted lines in their lowered position.

Fig. 6, is a side elevation of the lift, one of the flanges for securing the lift to the stirrup being omitted; and

Fig. 7, is an enlarged elevation of the quick acting mechanism looking in the opposite direction from Fig. 1.

In carrying out my invention as here embodied 1 represents an ordinary tank or receptacle in which is secured the stationary siphon 2, the lower end of which projects through the bottom of the tank and is secured thereto by a nut 3 run upon the threaded shank of said siphon; the protruding end of said shank serving to couple the siphon to a water closet or other device.

Within the intake end of the siphon is located the lift 4 which has the openings therethrough and upon this lift are hinged leaves 6, so as to normally lie flat upon the upper surface of the lift and having a swinging movement to the position shown in full lines in Fig. 5. This lift is secured to the stirrup 7 which latter in turn is suspended from the operating lever 8. The operating lever 8 is pivoted at 9 to a plate 10, which plate is secured to the front wall of the tank by the shank 11 which passes through said wall and has a nut 12 threaded thereon for securing the plate in proper position.

A shaft 13 passes through the shank 11 and carries upon its inner end a cam disk 14 provided with a cam 15, and to this disk is attached one end of the spring 16, the other end of said spring being attached to the lever 8 at 17. This cam disk is limited in its rotation against the action of the spring by a stop 18 against which the lug 19 projecting from said disk is adapted to strike, and the lever 8 is limited in its upward and downward swing by the stops 20 and 21 respectively. On the outer end of the shaft 13 is secured a handle 22 for operating the cam disk through the medium of the shaft.

From the foregoing description the operation of my invention will be obviously as follows:

The tank having been filled with water through the intake valve 23 to the point just below the upper edge of the bridge of the siphon as indicated by the water level line 24 and the further inflow of water be-

ing shut off by the ball float 25 in the usual manner, a quick upward movement of the lift 4 will cause the water in the intake leg of the siphon to fill the crown of said siphon flowing over the bridge 26, thus giving the siphon its initial start, when thereafter the water will continue to flow through the siphon to the closet until the tank has been emptied to the level of the mouth of the intake, this flowing of the water through the siphon being permitted by the hinged leaves swinging upward to the position shown in full lines in Fig. 5, and when the water has ceased flowing, these leaves will return to their normal, original position, closing the openings 5 in the lift and establishing the normal condition of the apparatus for further operation.

It is to be noted that when the flow of the water has once been started in the siphon, it cannot be interrupted by the user, and therefore a perfect flushing of the closet will take place, and it is to be further noted that when the tank has once been emptied, the siphon cannot again be started until the water has reached the proper level in the tank to get a complete flushing of the closet at the next operation, thus avoiding emptying a half tank or more of water without producing the desired result.

The quick upward movement of the lift above referred to is effected by the depression of the handle 22 which will rotate the cam disk 14 in the direction of the arrow in Fig. 7, stretching the spring 16, causing it to draw upon the lever 8 with a large tendency to move said lever upward, but at the beginning of the rotation of the cam disk, the point of the cam 15 passes over the lug 27 projecting from said lever, thus preventing the lever from being drawn upward by the spring until the spring has been stretched to the desired tension, at which time the heel of the cam will have passed the lug 27, freeing the same and permitting the spring to draw the lever upward with a quick movement, which in turn will impart this quick upward movement to the left. When the handle 22 is released the mechanism will return to its normal position, as will be readily understood.

In the construction of the siphon I prefer the design here shown in which the intake leg thereof is relatively of large capacity, gradually tapering to the crown from which point the outlet leg gradually converges into the round outlet shank. This arrangement causes the upward movement of the lift to displace a relatively large volume of water, so as to insure the filling of the crown and giving the siphon its proper initial start, thereby relieving the necessity of having the lift fit snugly within the intake end of the siphon, since any slight leakage will not affect the operation.

While the lift may be made in any suitable manner the construction here shown is preferred and consists of a metal plate having the stock from which the openings 5 are formed turned downward and clamped or crimped upon the stirrup 7, as clearly shown in Figs. 5 and 6, and also having the flanges 28 formed therewith, through which are suitable holes for hinging the leaves 6 to the lift and further having the inturned lugs 29 which serve as stops to limit the upward movement of the leaves.

While the stirrup may be attached to the lever in any suitable manner I have here shown it as being suspended in a slot 30 formed in the outer end of the lever and secured against displacement by the tie wire 31.

Of course I do not wish to be limited to the exact details of construction as here shown, as these may be varied within the limits of the appended claims without departing from the spirit of my invention.

Having thus fully described my invention, what I claim as new and useful, is—

1. The combination of a siphon of the character described, a lift consisting of a plate having openings therethrough, flanges formed with the plate, said flanges having holes therein, leaves hinged to the plate by pintles thereof projecting through said holes, lugs formed upon the flanges for limiting the upward swing of the leaves, and a connecting stirrup to which said lift is secured by the clamping of a portion of the metal of the plate upon the ends of the stirrup as shown and described.

2. In combination with a siphon of the character described a lift located in the mouth thereof, a pivoted lever, a stirrup connecting said lift with said lever, a cam disk carrying an operating handle, a spring connecting the cam disk and lever, a lug projecting from the lever, a cam carried by the cam disk engaging said lug, a plate to which the lever and disk are pivoted, and suitable stops upon the plate to limit the movements of the lever and cam disk.

3. In a flush tank of the character described the combination of a stationary siphon located within said tank, one end of which projects through the bottom thereof, a lift located within the mouth of the siphon and adapted to have a free vertical sliding movement therein, said lift having passageways therewith, leaves hinged to said lift and adapted to normally close the passageways, said leaves being adapted to swing upward with the flow of water through the siphon, a lever to which the lift is connected, a hand operating handle, a spring connecting said handle to the lever, a cam also carried by said handle and a lug carried by the lever which said cam is adapted to engage to prevent the upward movement of

the lever while the spring is being drawn to its maximum tension, whereby said lever will be given a quick upward movement at a predetermined point in the operation of

5 the handle.

4. In a flush tank a siphon having its outlet end projecting through the bottom of said tank, a lift fitted to slide loosely within the intake leg of said siphon, a suspended

10 stirrup extending downward on the outside of the siphon, the lower portion of said stir-

rup projecting upward into the mouth of the siphon and supporting the lift, an operating lever from which the stirrup is suspended, a hand lever, and means for giving 15 the operating lever a quick upward movement at a predetermined time, relative to the movement of the hand lever.

In testimony whereof, I have hereunto affixed my signature.

SAMUEL S. WILLIAMSON.
